No. 37,090.

Patented August 16, 1904.

UNITED STATES PATENT OFFICE.

FREDERICK W. GRELL, OF NEW YORK, N. Y., ASSIGNOR TO AMERICAN HARD RUBBER COMPANY, OF NEW YORK, N. Y., A CORPORATION OF NEW YORK.

DESIGN FOR A COMB.

SPECIFICATION forming part of Design No. 37,090, dated August 16, 1904.

Application filed May 12, 1904. Serial No. 207,702. Term of patent 14 years.

To all whom it may concern:

Be it known that I, FREDERICK W. GRELL, a citizen of the United States, residing at College Point, in the borough of Queens, city and State of New York, have invented a new, original, and ornamental Design for Combs, of which the following is a specification, reference being had to the accompanying drawing, forming a part thereof.

10 The figure represents the new design for combs in perspective.

What I claim, and desire to secure by Letters Patent, is—

The new, original and ornamental design for a comb substantially as shown.
